UNITED STATES PATENT OFFICE.

WALTER MORTON BROWN, OF ALBANY, NEW YORK.

INK-WELL FOR DESKS.

SPECIFICATION forming part of Letters Patent No. 444,876, dated January 20, 1891.

Application filed November 10, 1890. Serial No. 370,896. (No model.)

To all whom it may concern:

Be it known that I, WALTER MORTON BROWN, a citizen of the United States, residing at Albany, in the county of Albany and 5 State of New York, have invented certain new and useful Improvements in Ink-Wells for Desks; and I do declare the following to be a full, clear, and exact description of the invention, such as will enable others skilled in 10 the art to which it appertains to make and use the same, reference being had to the accompanying drawings, and to the figures of reference marked thereon, which form a part of this specification.

15 The object of my invention is to provide an ink-well for desks, &c.

In the drawings, Figure 1 shows a cross-sectional view of a desk-top, an ink-well cover, and a vertical sectional view of an ink-well 20 held in position by a spring, the well being open for use. Fig. 2 shows a plan view of a portion of the under side of a desk-top, showing the configuration of the opening in the lower side of the desk-top to receive the ink-well. Fig. 3 shows a plan view of the ink-well, the inner circle showing that the well may be tapered. Fig. 4 shows a similar view 25 to Fig. 1, but showing the well closed. Fig. 5 shows a longitudinal sectional view of a desk-top without a separate cover for the well, the pen-hole being bored through the desk-top and reamed out, the ink-well standing in the lower opening, as in Figs. 1 and 4.

A full description is as follows: I make a 35 circular hole, preferably in the top of the desk, and permanently and immovably fasten a cover 2 therein, having a pen-hole 3 through it. From the under side of the desk and eccentrically with the hole containing the cover, 40 I make an oblong slot 4, preferably as shown in Figs. 1, 2, 4, and 5. I provide an ink-well 5, having a flange 9 projecting from two of its sides, preferably, the well and its flanges being made to fit in the slot 4, as shown in 45 Figs. 1 and 4, the width of the slot and that of the well and flanges being such as to allow the well 5 to enter the slot 4, and the length of the flanges 9 being such as to allow the well to slide back and forth in the slot. I 50 preferably set the well 5 on a spring 6 to hold it in position, and the free end 7 of the spring

I cause to engage with the catch 8, so as to prevent the spring 6 being bent down until the end 7 is disengaged with the catch 8, and I fasten the spring to the desk in any well-known manner.

The operation is as follows: The well being in position, as shown in Fig. 1, the pen-hole 3 coincides with the mouth of the well 5, and a pen may be dipped into it. The well is 60 therefore open and is held in position and caused to press lightly against the bottom of the slot 4 by the spring 6. When it is desired to close the well, it is simply pushed along the spring 6 until the rear flange 9 covers the pen-hole and the mouth of the well is closed by laying under the cover 2 and desk-top 1, as shown in Fig. 4. The cover may be omitted and a pen-hole 3 cut through the desk-top 1 and be in communication with slot 70 4, as shown in Fig. 5, if desired, and when the desk-top is made of hard wood it is a very cheap way of constructing the apparatus, as it saves the expense of the cover 2.

Having fully described my invention, what 75 I claim is—

1. A desk having a pen-hole through its top and having a coverless ink-well with its upper edge or mouth continuously held against the under side of the desk-top and 80 arranged to be moved so that the mouth of the well will coincide with or recede from the pen-hole, substantially as described.

2. A desk-top having an opening in its under surface to receive an ink-well and a pen-hole through its top surface in communication with the opening in its under surface, and an ink-well removably held in said opening with its upper edge or mouth pressed against the desk-top, said well being arranged 90 to move in its opening in the desk-top in order that the opening or mouth of the well may be made to coincide with or recede from said pen-hole at will, and the well be thus opened or closed, substantially as described. 95

3. An ink-well removably held in communication with a desk-top by a spring, said spring being attached to the desk by one end, but free at its other end, the free end of said spring being arranged to engage with a catch 100 in order that said spring may securely hold the well in place, substantially as described.

4. A desk-top having an ink-well cover sunk therein, its upper surface flush with or below the upper surface of the desk-top, said cover having a pen-hole therein through which a pen may be passed, and having an ink-well whose mouth is retained underneath said cover and arranged to be moved so that the mouth of said well may be made to coincide

with or recede from the pen-hole in said cover, substantially as described.

In testimony whereof I affix my signature in presence of two witnesses.

WALTER MORTON BROWN.
